WAVEGUIDE ANTENNA WITH NON-RESONANT
SLOTS

Robert F. Morrison, Jr., Washington, D.C., assignor to
the United States of America as represented by the Sec-
retary of the Army

Filed Mar. 28, 1951, Ser. No. 218,059
1 Claim. (Cl. 343—705)

This invention relates to waveguide antenna arrays, particularly to waveguide antenna arrays having non-resonant slots and capable of transmitting electromagnetic waves in narrowly defined and highly directional beams.

Normally, waveguide antennas of rectangular cross section have cut in one of the broad faces of the guide two rows of longitudinally spaced resonant slots. Each slot is spaced from the longitudinal axis of the broad surface with the longitudinal axis of each slot paralleling the longitudinal axis of the broad surface. The amount of radiation from each slot in the row is controlled by varying the spacing between the longitudinal axis of each slot and the longitudinal axis of the broad surface. The more closely the longitudinal axis of a slot approaches the longitudinal axis of the broad surface, the lower the amount of radiation therefrom. Since the slots are arranged in two rows and staggered relative to each other, an overlapping or intersection of slots may occur when both rows are placed at or extremely close to the longitudinal axis of the broad face to obtain minimum radiation. The use of pins or stubs adjacent to the slots on the inner wall of the wave-guide has also been employed in the past as a means to control the amount of radiation from the slots. This method has proven to be time consuming and costly in mass production.

The directivity of the radiation pattern of slotted waveguide antennas is usually controlled by varying the longitudinal spacing between slots. For example, a spacing of one-half wavelength between resonant slots will result in maximum radiation normal to the longitudinal axis of the waveguide antenna. A spacing greater than one-half wavelength will result in radiation at an angle to one side of the plane normal to the longitudinal axis of the waveguide antenna and a spacing less than one-half wavelength will result in radiation at an angle to the opposite side of the plane normal to the longitudinal axis of the waveguide antenna.

A primary object of the invention is a slotted waveguide antenna having great structural strength.

Another object of the invention is a microwave antenna array wherein the radiating slots of the waveguide are arranged to prevent overlapping.

Another object of the invention is a microwave antenna array wherein the staggered slots in the elements of the array are arranged to avoid intersection of each other.

Another object of the invention is a waveguide antenna having novel means for forming the radiation pattern.

Another object of the invention is a novel means for controlling the amount of radiation of a waveguide antenna.

Another object of the invention is a waveguide antenna having novel directivity means incorporated therein.

Another object of the invention is the elimination of probes adjacent to the slots for controlling the amount of radiated energy of a waveguide antenna.

The specific nature of the invention as well as other objects and advantages thereof will clearly appear from the following description and accompanying drawings in which:

FIGURE 1 is a perspective view showing a section of a conventional waveguide antenna wherein the resonant slots are closely spaced with respect to the longitudinal axis of the waveguide.

2

FIGURE 2 is a plan view of the slotted waveguide antenna of the invention.

FIGURE 3 shows the radiation pattern of the waveguide antenna of FIGURE 1, illustrating output in deci-
5 bels in relation to the antenna axis.

FIGURE 4 is a typical plot illustrating the relationship
of the slot length to the slot conductance; and

FIGURE 5 is a perspective view showing four slotted
waveguide antennas embodied in the nose of a missile.

The desired radiation pattern for the waveguide antenna of the invention is obtained by choosing a suitable combination of slot dimensions and longitudinal spacing between slots. The slot spacing is given by the following formula:

$$d = \frac{\lambda\lambda g}{2(\lambda - \cos \theta\lambda g)}$$

where

20 d =longitudinal spacing between slot centers.

λ =free space wavelength.

λg =wavelength in the guide.

θ =angle of the major lobe.

25 The slot size depends upon the required slot conductance. The required slot conductance is obtained from the following formula:

$$30 G_n = \frac{P_n}{P_L + \sum_{k=1}^{n-1} P_k}$$

G_n =normalized conductance of the nth slot.

P_L =percentage power dissipated in the load terminating
35 the antenna.

P_k =percentage power radiated by the kth slot.

P_n =percentage power to be radiated by the nth slot.

40 The manner in which P_n varies with n depends upon the desired radiation pattern. In some cases, P_n is a constant, while in others, P_n is small near the ends of the antenna and large near the center. Once G_n is determined, the slot length is obtained from the curve shown in FIGURE 4.

45 FIGURE 1 of the drawings shows a conventional type of waveguide radiator in which 1 indicates the waveguide of rectangular cross section. Radiation means comprising slots 3 and 4 are formed in the wall 2 of the waveguide, parallel to the longitudinal axis of the wall. For 50 certain directivity characteristics and radiation power, it is necessary that the slots be longitudinally spaced less than one-half wavelength, resulting in the waveguide wall being weakened in the areas between the adjacent ends of the opposing slots of each of the series of slots.

55 The present invention eliminates the possibility of positioning the slots so that overlapping at the axis can occur, for all slots of the array of the invention are well and equidistantly spaced from the longitudinal axis of the waveguide wall. The amount of radiation from each slot 60 is controlled by the length of the slot rather than by its distance from the longitudinal axis of the waveguide wall.

Referring now to FIGURE 2, wherein there is shown one embodiment of the waveguide array of the invention comprising a waveguide 5 having a row of radiating slots 6 on each side of the longitudinal axis 6-6 of one of the broad faces 7 of the waveguide. Each row is equidistantly spaced from the longitudinal axis. The slots 8 are a half-wavelength long, the slots 9 are somewhat shorter and the slots 10 are shorter still. Thus, maximum radiation will take place through the resonant slots 8, while the radiation will be reduced through the progressively non-resonant slots 9 and 10.

FIGURE 3 shows the radiation pattern produced by the slot pattern of the waveguide of FIGURE 2. However, it is to be noted that various radiation patterns can be obtained as may be desired by selected arrangement of slot size and spacing in accordance with the formulas listed above.

Several of the slotted waveguide antennas may be placed on the surface, or may comprise a portion thereof, of a cylinder or cone to produce a radiation pattern which is omnidirectional in the plane perpendicular to the axis of the cone, but highly directional in the plane containing the axis of the cone. The number and distribution of the slotted waveguide antennas depends upon the allowable variation in beam angle and radiated power as the cone is rotated about its axis. The variation in beam angle is due to the fact that the cone axis and waveguide axis are not parallel. The power variation is due to interference effects and directivity of the individual antennas. An embodiment of the foregoing is shown in FIGURE 5 wherein four radiating elements 11, 12, 13 and 14 are disposed at equal intervals around the conical nose 15 of a missile 16. The elements 11, 12, 13 and 14 are supplied with microwave energy from a common source such as a transceiver 17 by means of waveguide feeders 18, 19, 20 and 21, respectively. Accordingly, an explosive missile, having an aerodynamic surface, may be provided with a microwave antenna array conforming to the aerodynamic surface. Obviously, the antenna array is adapted to produce an omnidirectional radiation pattern in azimuth about the longitudinal axis of the missile and inclined in elevation as desired in respect to the direction of flight of the missile.

I claim:

In an explosive missile having an aerodynamic surface, a microwave antenna array conforming to said aerodynamic surface and producing an omnidirectional radiation pattern in azimuth about the longitudinal axis of said missile and inclined in elevation as desired in respect to the direction of flight of said missile, said array comprising a multiple of waveguide radiators fixed in spaced relationship in the peripheral surface of the nose of said missile, microwave generating means fixed within the said nose, each of said waveguide radiators connected to said generating means by waveguide feeders, each of said waveguide radiators having formed in one wall thereof two rows of microwave radiating means in staggered relation to each other and equidistantly spaced from the longitudinal axis of said wall, said microwave radiating means comprising resonant slots in said wall intermediate the ends of said wall and progressively non-resonant slots on each side of said resonant slots towards the ends of said wall to form a microwave radiation beam having its major lobe intermediate said ends, the said beam of each waveguide contributing to form said omnidirectional radiation pattern.
